UNITED STATES PATENT OFFICE.

LYLE H. ETTER, OF MARIETTA, OHIO.

METALLIC WEATHER STRIP.

Application filed February 14, 1922. Serial No. 536,606.

To all whom it may concern:

Be it known that I, LYLE H. ETTER, a citizen of the United States, residing at Marietta, in the county of Washington, and State 6 of Ohio, have invented a new and useful Metallic Weather Strip, of which the following is a specification.

This invention relates to weather strips and particularly to metallic weather strips.

10 The object is to provide weather strips of thin flexible metal to be cut in suitable lengths for attachment to window frames and door frames for the purpose of excluding wind, snow and rain, and also to form 15 a track, in the case of a window, for the latter to slide upon, thus reducing the friction and permitting the upward and downward movement of the window sash with a minimum effort.

20 Another object is to provide a strip for this purpose which has a double bearing surface against the window sash or door for the purpose of effectively sealing the space between the same and the frame, the weather 25 strips being so constructed as to be easily applied in position without the necessity of removing the sashes as is usually the case with ordinary strips.

20 A further object is to provide weather strips which will prevent the sashes from binding in their tracks or grooves in the window frames, all side play and rattling being prevented by the spring pressure of the strips at two different points on all sides 35 of the sash.

30 A full and complete understanding of the invention may be obtained from a consideration of the following detailed description, taken in connection with the accompanying 40 drawing forming a part of this application; it being understood that while the drawing shows a practical form of the invention, the latter is not confined to strict conformity therewith, but may be changed or modified, 45 so long as such changes or modifications mark no material departure from the salient features of the invention, as specifically pointed out in the appended claims.

50 In the drawing, in which similar reference characters designate corresponding parts throughout the several figures:—

55 Fig. 1 is a vertical section through the upper portion of a window frame having the improved weather strip applied thereto, the outer or upper sash being shown in lowered position.

Fig. 2 is a similar view, the sash being elevated to its seat and showing the weather strip engaged thereby.

Fig. 3 is a horizontal sectional view taken 60 on the line 3—3 of Fig. 1, and looking in the direction of the arrow.

Fig. 4 is a similar view, taken on the line 65 4—4 of Fig. 2, and looking in the same direction.

Fig. 5 is a detail perspective view of a portion of the strip.

Referring to the drawing, there is shown the upper portion 1 of an ordinary window frame having the usual sash guides or 70 grooves 2 for the upper and lower sashes, the upper cross bar or rail 3 of the outer or upper sash being illustrated in a slightly lowered position, all of which may be of any form of construction and needs no 75 detailed description, the improved weather strip being applicable to all forms of window and door frames.

The weather strip, as shown in Fig. 5, comprises an angularly bent strip of thin 80 metal, preferably of brass or some other equally resilient, non-corrodible metal, the angle thereof extending longitudinally 85 throughout its length, such length being the usual length of stock material of this class which is designed to be cut into the desired lengths to suit the particular frames to be supplied.

The longitudinal angle 4 of the strip is 90 located at one side of the center line of the same and provides a face or portion 5 and a face or portion 6, defining between the same an acute angle somewhat less than ninety degrees, and designed to form attaching portions or bases to be alternatively used 95 along the sides of a frame or at the top or bottom thereof for attaching the strip in position.

The faces or portions 5 and 6 extend 100 different distances from the angle 4 and are each imperforate, the metal comprising the strip being thin enough to permit driving a nail or a tack therethrough, for holding the strip in place, although it is to be understood that the same may be formed of thicker and stouter material and provided with apertures for the passage of nails, tacks or screws. The face or portion 6 is of greater width than the face or portion 5.

105 The portion or face 6 is bent longitudinally of the strip in an inward direction at an incline, as shown at 6^a, and is then bent

opposite or outwardly, as at 6^b, to form an angular track 7 extending throughout the length of the strip where the two inclined portions meet, and adapted to act 5 as a track of small area when used at the sides of the sash, and to reduce the friction thereof during the upward and downward movement of the same when raised or lowered, or to abut against the upper or lower 10 rails of the sash when used at the bottom thereof or at the top as shown in Fig. 2 of the drawing.

The strip as shown and described is used at the sides and top of the upper or outer 15 sash and at the sides and bottom of the lower or inner sash, the same strip being used though fastened in different ways. When attaching the strip at the sides of the window frame 1 to coat with the stiles 20 of the window sashes, the same is placed with the angle 4 thereof snugly fitting in the outer corner of the guide or groove 2 towards the outside or front of the window frame, as shown in Figs. 3 and 4 of the 25 drawing, and the fasteners 8 are driven through the face 6 thereof into the bottom wall of said channel 2. The free edge of the face 5, by reason of the acute angle between the faces 5 and 6, is in spaced relation 30 to the outer wall of the said guide or groove, and bearing against the face of the sash, as shown in Figs. 1 and 4 of the drawing, and the track 7 is also held in spaced relation to the bottom wall of the guide or groove and 35 capable of cushioning action against the sides of the sash as the same is raised or lowered. In this way, the same strip has a double bearing against the sash.

When the strip is applied as described, 40 the resiliency of the face 5 of the strip serves to urge the sash against the adjacent face of the parting strip 9 of the window frame and the strip is thus flexed by the same, the free edge of said face 5 springing inwardly 45 over the upper bar of the sash, when the latter is lowered, and thus causing a tight joint at all times between the inner face of the sash and the inner wall of the guide or groove 2.

The strips for coaction with the sides of the sashes need only be applied to the opposite upper halves of the outer guides or grooves for use with the upper sash and in the lower halves of the inner guides or 55 grooves to be engaged with the sides of the lower sash. When the strips are applied for use in conjunction with the upper bar of the upper sash the plain faces 5 of said strips are used for fastening the same in 60 position, said fasteners 8 being driven therethrough and into the inner face of the strip or bead forming the outer or front wall of the guide or groove at the top, as clearly 65 shown in Fig. 1 of the drawing. This results in the face 6 and track 7 carried there-

by being held in spaced relation to the bottom of the top guide or groove and in position to be struck by the top bar of the sash, when the same is raised. In like manner, the strip may be attached to the sill of 70 the window frame to be engaged by the bottom bar of the lower sash (not shown).

From the foregoing, it will be seen that an extremely simple and cheaply manufactured 75 weather strip for doors and windows has been provided which may be readily applied in proper position without the necessity of removing the sashes from the frame, and that the same is adapted to reduce the friction in elevating or lowering the sashes by 80 the provision of the tracks 7 bearing against the side bars of the sashes, and that the space between the sash and frame is effectively closed against the entrance of cold air or water, etc., by reason of the cushioning 85 effect of the free edge of the face 5, which also prevents any rattling of the sashes by effect of winds, etc.

It will be seen that the strip provides a 90 double joint along the sides of the sash by reason of the free edge of the face 5 bearing 95 against the outer face of the stiles of said sash, and the resilient tracks 7 bearing against the adjacent sides of the sash, and that the latter is held in perfect longitudinal alignment with the guides ready to be raised or lowered therein without any danger of the same wedging. It will be understood that the strips, when used in conjunction with a 100 swinging door, are placed against the abutment faces of the frame in the same manner as at the top of the window frame, that is with the fasteners passing through the face 5 of the angle strip, so that the door will 105 strike against the face 6 and track 7.

What is claimed is:—

1. A weather strip composed of a length of resilient metal bent longitudinally to provide faces or portions of different widths, the angle between the same being slightly less than ninety degrees, the face or portion of greater width having its free edge portion bent further toward the portion of lesser width to provide a longitudinally disposed resilient track. 110

2. A weather strip composed of a length of resilient metal bent longitudinally to provide faces or portions of different widths, the angle between the same being less than ninety degrees, the face or portion of greater width having its free edge portion bent further toward the portion of lesser width to provide a longitudinally disposed resilient track, and means for securing the face or portion of lesser width in the sash guide or groove of a window frame to cause the other face or portion with its track to bear against the sliding sash. 120

3. A weather strip composed of a length of resilient metal bent longitudinally to pro- 125

- wide faces or portions of different widths, the angle between the same being less than ninety degrees, the face or portion of greater width having its free edge portion bent 5 further toward the portion of lesser width to provide a longitudinally disposed resilient track, and means for securing the face or portion of greater width in the sash guide or groove of a window frame to cause the 10 free edge of the other face or portion to act as a cushion against the face of the sliding sash, and the track at the free edge of the first mentioned face or portion to engage the edge of the sash.
- 15 4. In combination with a grooved window frame and sash, a weather strip consisting of a strip of sheet metal bent longitudinally to provide two faces or portions arranged at an acute angle to each other, one of the faces 20 or portions being of greater width than the other, and the face or portion of greater width being provided at its free edge with an elevated resilient track formed by bending the metal first slightly inwardly and then 25 slightly outwardly at an angle, and means securing the strip in the guide or groove of the window frame with the narrow face or
- portion and the track both free, whereby the face of the sash is engaged by the narrow face or portion while the track bears against the side edge of the sash and constitutes both a cushion and a track for the sash in its movements. 30
5. A weather strip composed of resilient metal and bent longitudinally to form two plane portions at an acute angle to each other, the free longitudinal edge of one portion being bent slightly inwardly and then slightly outwardly, each of the last-mentioned bends being on a line parallel to the 35 first-mentioned bend.
6. A weather strip composed of a length of resilient metal bent longitudinally to provide faces or portions of different widths, the angle between the same being slightly less than ninety degrees, the face or portion of greater width being angularly bent intermediate its width to bring the free edge thereof further toward the portion of lesser width to provide a longitudinally disposed 40 45 resilient track.

In testimony that I claim the foregoing as my own, I have hereto affixed my signature.

LYLE H. ETTER.
